UNITED STATES PATENT OFFICE.

JOHN P. BUCHANAN, OF CLEVELAND, OHIO, ASSIGNOR OF ONE-HALF TO FREDERICK B. WIEGAND, OF CLEVELAND, OHIO.

RAILWAY SIGNALING.

1,177,377.

Specification of Letters Patent. Patented Mar. 28, 1916.

Original application filed October 29, 1913, Serial No. 797,988. Divided and this application filed May 7, 1914. Serial No. 836,935.

To all whom it may concern:

Be it known that I, JOHN P. BUCHANAN, a citizen of the United States, residing at Cleveland, in the county of Cuyahoga and State of Ohio, have invented certain new and useful Improvements in Railway Signaling, of which the following is a specification.

My invention relates to railway signaling 10 of the type in which the signals are controlled by track circuits.

More particularly, my invention relates to signaling of this type in which a block between signals is divided into two or more 15 sections each of which is provided with an isolated track circuit.

The present application is a division of my co-pending application filed October 29, 1913, Serial No. 797,988, for relays.

20 I will describe one form of signaling system embodying my invention, and will then point out the novel features thereof in claims.

25 The accompanying drawing is a diagrammatic view showing one form of signaling system embodying my invention.

Referring to the drawing, I have here shown a stretch of railway track which is divided into successive blocks A—B, B—C, 30 etc. Located adjacent the entrance ends of the blocks are railway signals S^A, S^B, etc., each of which is adapted to indicate "danger," "caution" and "clear;" as here shown, these signals are of the semaphore type and each signal comprises a single arm 35 adapted to assume three indicating positions, but it is understood that any type of signal adapted to give the three said indications may equally well be employed.

40 Each block is divided into two sections, the sections for block A—B being A—a and a—B, and those for the other blocks being similar. As here shown, the rails of each section are electrically isolated from those 45 of the adjacent sections by insulated joints 2.

Each section is provided as usual with a track circuit comprising the rails of the section, a source of current 35 or 36 (here 50 shown as being batteries) and a relay R or R'. The relay R for the first section of each block controls the signal for the corresponding block, and may be of any suitable type adapted to assume three controlling posi-

tions; for example, each of these relays may 55 be of the type shown in my application Serial No. 797,988, of which the present application is a division, the contact arrangement being the same as that shown in Fig. 3, except that contacts 22, 31 and 32 60 are omitted. Each of these relays comprises a winding 11 connected with the track rails, and a contact 21 which closes the caution indication circuit of the signal when the relay is energized in one direction and both 65 the caution and clear indication circuits when the relay is energized in the other direction. The relay R' for the section at the exit end of each block is employed to control the supply of current to the rails of the 70 section in the rear, and as here shown these relays are of the type shown in my application, Serial No. 797,988, the contact arrangement being the same as that shown in Fig. 5 75 of said application. Briefly described, each of these relays comprises a winding 11 connected with the track rails, a cam 19^a actuated by the relay armature, and two contact fingers 31^b, 32^b controlled by the cam. As pointed out in the copending application of 80 which the present case is a division, the armature of the relay, and consequently the cam 19^a, are biased to assume a middle position when the winding 11 is deenergized, and are swung in one direction or the other 85 from this middle position when the winding is energized in one direction or the other. The cam and fingers are so arranged that when the armature occupies its middle position, both fingers touch a contact 26; when 90 the armature swings in one direction the cam 19^a moves finger 31^b away from contact 26 and into engagement with contact 28; and when the armature swings in the other direction the cam moves the other 95 finger 32^b away from contact 26 and into engagement with contact 27. The contact fingers 31^b and 32^b are connected with the track rails respectively, one terminal of battery 36 is connected with contact 26, and 100 the other battery terminal is connected with both contacts 27 and 28. Hence, when the relay armature is swung to one extreme position or the other, battery 36 is connected with the track rails in one direction or the 105 other, and when the armature occupies its middle position the battery is disconnected from the rails and the rails are connected.

- by a low-resistance shunt comprising fingers 31^b and 32^b and contact 26. Each signal operates a pole-changer for reversibly connecting the battery 35 with the rails of the 5 track section immediately in the rear of the signal; the battery 35 is connected with the rails in one direction when the signal indicates clear and caution, and in the other direction when the signal indicates danger.
- 10 The operation of the system is as follows: Since the section at the exit end of the block at the right-hand end of the drawing is occupied by a train W, relay R' for this section is deenergized, so that the battery 36 is disconnected from the rails of section C—c, and the rails of this section are connected by a low-resistance shunt. Relay R for section C—c is therefore deenergized so that signal S^c indicates danger.
- 15 Pole-changer P operated by this signal then connects battery 35 with the rails of the section b—C in the rear in such direction that contact 31^b of relay R for this section is moved into engagement with contact 28.
- 20 Relay R for section B—b is then energized in such direction as to cause signal S^b to indicate caution. The pole-changer P operated by this signal is therefore in such position that relay R' for section a—B is
- 25 energized in the direction opposite to that of the corresponding relay for block b—C so that relay R for section A—a is energized in such direction as to cause signal S^a to indicate clear.
- 30 It will be noted that when the car or train occupies the section at the exit end of a block the rails of the other section for such block are placed on short circuit by the relay R' so that this relay is the equivalent
- 35 of a car or train on the latter section and the possibility of false operation of the relay for the latter section by stray or foreign current is greatly reduced.
- Although I have herein shown and de-40 scribed only one form of railway signaling system embodying my invention, it is understood that various changes and modifications may be made therein within the scope of the appended claims without departing 45 from the spirit and scope of my invention.
- Having thus described my invention, what I claim is:
1. In combination, two sections of a railway track, a source of current, means for 50 reversibly connecting said source with the track rails of one section, a relay energized from the rails of the same section and having a member adapted to assume a middle position when the relay is deenergized and 55 to move in one direction or the other from
- said position when the relay is energized in one direction or the other, a source of current for the other section, and contacts included in said relay and controlled by said member for placing the rails of the latter 60 section on short circuit when the member occupies its middle position, and for connecting said latter source of current with the rails of the latter section in one direction or the other when the member moves 65 in one direction or the other from its middle position.
2. In combination, a railway track section, a source of current, a relay having a member adapted to assume a middle position when the relay is deenergized and to move in one direction or the other therefrom when the relay is energized in one direction or the other, means for reversibly energizing said relay, and contacts included in said 70 relay and controlled by said member for placing the rails of said track section on short circuit when said member occupies the middle position, and for connecting said source of current with said rails in one direction or the other when the member moves 75 in one direction or the other from its middle position.
3. In combination, two sections of a railway track, a source of current for one of said sections, means for reversibly connecting said source with the track rails of said section; a relay energized from the rails of the same section and having a member adapted to assume a middle position when the relay is deenergized and to move in one direction or the other from said position when the relay is energized in one direction or the other, a central stationary contact and two outside stationary contacts, a source of current having one terminal connected with said central contact and the other terminal connected with both outside contacts, two contact springs biased to engagement with said central contact and connected respectively with the rails of the other track section, one of said springs being moved from the central contact to an outside contact when the member moves in one direction from its middle position and the other spring being moved from the central contact to the other outside contact when the member moves in the other direction from its middle position.
- In testimony whereof I affix my signature 115 in presence of two witnesses.
- JOHN P. BUCHANAN.
